(57) **CLAIM**

The ornamental design for an earphone case, as shown and described.

DESCRIPTION

FIG. 1 is a front perspective view of an earphone case, showing a first embodiment of our new design;

FIG. 2 is a front view thereof;

FIG. 3 is a back view thereof;

FIG. 4 is a top view thereof;

FIG. 5 is a bottom view thereof;

FIG. 6 is a right side view thereof;

FIG. 7 is a left side view thereof;

FIG. 8 is a back perspective view thereof;

FIG. 9 is a front perspective view thereof, shown in an environmental use;

FIG. 10 is a back perspective view thereof, shown in an environmental use;

FIG. 11 is a front perspective view of the earphone case, showing a second embodiment of our new design;

FIG. 12 is a front view thereof;

FIG. 13 is a back view thereof;

FIG. 14 is a top view thereof;

FIG. 15 is a bottom view thereof;

FIG. 16 is a right side view thereof;

FIG. 17 is a left side view thereof;

FIG. 18 is a back perspective view thereof;

FIG. 19 is a front perspective view thereof, shown in an environmental use; and,

FIG. 20 is a back perspective view thereof, shown in an environmental use.

The broken lines showing earphones in FIGS. 9, 10, 19 and 20 depict the environment of the claimed design, and form
